UNITED STATES PATENT OFFICE.

WILLIAM J. ROSTERN, OF NEW YORK, N. Y.

CONTAINER FOR INNER TUBES FOR PNEUMATIC TIRES.

Application filed July 28, 1923. Serial No. 577,516.

To all whom it may concern:

Be it known that WILLIAM J. ROSTERN, a citizen of the United States, residing at the borough of Bronx, county of Bronx, city and State of New York, has invented new and useful Improvements in Containers for Inner Tubes for Pneumatic Tires, of which the following is a specification.

The present invention relates to improvements in containers or protectors for inner tubes for pneumatic tires.

As is well known, it is customary in motor vehicle operation to carry one or more so-called spare tubes for use in making replacements of those punctured or otherwise damaged. These spare inner tubes are usually carried in a tool box or compartment of the vehicle and when unprotected by some suitable wrapping are frequently injured by tools or other objects coming in contact therewith. Furthermore, the inner tube manufacturers recommend that the tubes be folded upon themselves so that the valve stems will protrude between the opposite ends of the folded halves of the tubes, to obtain the most satisfactory results in transportation. Obviously if the tubes are so folded, the metallic valve stem will contact with the tube walls and chafe the same so that the tube is frequently weakened and rendered unfit for service.

Efforts have been made to provide containers or protectors for the aforesaid inner tubes but they have not been of the character which would warrant their general adoption by reason of the relatively high cost of manufacture and the fact that the tubes could not be located therein with the ease and facility which is demanded by the motorist.

The general object of the present invention is to provide a simple and economical inner tube container or protector which is so designed that the inner tube, when folded as prescribed by the tube manufacturers, may be inserted therein with the utmost facility and despatch, the inner tube being positively protected against damage by tools or other objects or by the valve stem coming in contact with the walls thereof.

My invention also comprehends an inner tube container or protector which is formed of a water proof and oil proof material and which when the tube is properly located therein, and the container or protector closed, will materially decrease the tendency to de-

terioration of the tube from variations in the atmospheric conditions.

Further objects and advantages of my invention will become obvious as the description proceeds and I would have it understood that I hold unto myself all rights, to the full range of equivalents both in structure and use, to which I may be entitled under my invention in its broadest aspect. 65

For the purposes of the present disclosure I have illustrated certain preferred embodiments of my invention. My invention however is not limited to the structure shown, as various changes in details may be made without departing from the spirit and scope thereof as defined in the appended claims. 70

In the drawings, Fig. 1 is a view in perspective of a container or protector made in accordance with my invention showing an inner tube positioned therein; 75

Fig. 2 is a longitudinal section of the structure shown in Fig. 1, the sealing flap being in closed position;

Fig. 3 is an elevation of my improved 80 container or protector for inner tubes, showing the two halves thereof folded upon themselves, their free ends being tied together to form a compact package;

Figs. 4 and 5 respectively are plan views 85 of modified forms of the invention shown in Figs. 1 to 3 inclusive.

Referring now to the drawings in detail in which like characters of reference are used to designate similar parts throughout the several views, 7 indicates the body portion of the container or protector which is preferably formed from a fabric which has been treated to render it impervious to moisture such, for instance, as oil-cloth and similar materials. It will be observed that the body portion 7 of the container or protector is cut in an elongated rectangular configuration and is of a length and width slightly greater than the over-all length and width of the inner tube 8, when the ends thereof are folded upon themselves as shown in Fig. 2. 90

Secured to the body portion 7 are the pieces 9 and 10 respectively which conform to the shape of the contiguous parts of the body portion 7, the registering sides and end edges of the respective pieces 9 and 10 and the body portion 7 being joined by means of stitching, cement or any other suitable material. For instance, if desired, and to improve the appearance of the container or protector as a whole, the registering edges 105 110

of the pieces 9 and 10 and the body portion 7 may be finished with a binding or piping as shown at 11.

From the construction described, it will be seen that my improved container or protector for inner tubes embodies two compartments or envelopes, the opposed openings or mouths of which are in spaced relation.

In the employment of my invention, the inner tube 8 is folded in the customary manner with the valve stem located intermediate of its ends. One end of the tube is then inserted in one of the compartments or envelopes formed by the pieces 9 and 10 united to the body portion 7, after which the other end of the tube is similarly located in the remaining compartment or envelope. As will be noted the piece 9 is formed with a preferably integral extension or flap 9^a which is of a length sufficient to bridge or cover the space between the openings or mouths of the respective compartments or envelopes and enter the compartment formed by the piece 10 secured to the body portion 7. When the tube has been inserted in the body portion 7 as described, this flap 9^a, which is provided with a slit or opening 9^b to permit the valve stem 8^a to project therethrough, is inserted within the opposite compartment so that it will assume the position shown in Fig. 2. The inner tube is thus completely covered and no part of the wall thereof is exposed to injury or damage by any objects which may come in contact with the container or protector.

The container or protector may be employed in its flattened or extended form as shown in Fig. 2 or, if a more compact package is desired, the ends thereof may be folded over upon themselves, the folded halves being held together by tying the tapes or ribbons 12 suitably secured to the opposite ends thereof. As shown in Fig. 3 the valve stem 8^a is housed between the two halves of the container or protector and cannot possibly come into contact with the walls of the tube and chafe or otherwise injure the same. Furthermore, the valve stem itself is protected against mutilation of the threads thereof which frequently results from tools or other objects coming in contact with the same.

In the modified form of my invention shown in Fig. 4, in lieu of the flap 9^a, formed by the extension of the piece 9, I provide a flap 13 made integral or otherwise suitably secured to the side edges of that part of the body portion 7 which lies between the mouths or openings of the two compartments or envelopes of the container. This flap 13 is of a sufficient width to permit of the insertion of the edges thereof within the opposite compartment so that the tube is wholly enclosed within the protecting walls 65 of the container.

The embodiment of my invention shown in Fig. 5 comprises an elongated envelope within which the tube is adapted to be inserted as in the structure shown in the preceding figures, the valve stem 8^a protruding through the slit or opening 14 in the wall 15 of the envelope. The open end of the envelope 15 is closed by an integrally or otherwise formed flap 16 which may be held in closing position by means of a button 17 and a co-operating clasp 18.

While I have described my invention in reference to the specific structures herein shown, it will be obvious that my invention may take other forms without departing from the spirit and scope thereof. For instance, in lieu of the slit 9^b, an orifice of any other suitable shape may be provided to permit of the passage of the valve stem 8^a through the flap. Further the compartments may be formed by blanking out complementary extensions or flaps on the body portion 7, which may be suitably joined together for the purpose; likewise, in lieu of the tapes or ribbons 12, snap fasteners or other suitable devices may be used to connect the ends of the halves of the container or protector when it is folded to form a package as shown in Fig. 3.

What is claimed is:

1. A container for inner tubes for pneumatic tires embodying two permanently formed compartments, each thereof being provided with an open end, the open ends of said compartments being oppositely disposed and spaced from each other to permit of the insertion of a folded half of an inner tube in each compartment in a manner whereby the valve stem of said inner tube will occupy the space between said compartments.

2. A container for inner tubes for pneumatic tires embodying two oppositely disposed spaced compartments, each being open at one end to receive one half of a folded inner tube and a single element for closing the open ends of both of said compartments.

3. A container for inner tubes for pneumatic tires embodying two compartments having oppositely disposed spaced open ends, each compartment being adapted to receive one half of a folded inner tube in a manner whereby the valve stem of the inner tube will be located between said compartments, and a closure for the open ends of said compartments, said closure being provided with an opening to permit the valve stem to project therethrough.

4. A container for inner tubes for pneumatic tires formed from flexible water-proof material and provided with two compartments having oppositely disposed open ends, each compartment being adapted to receive one half of a folded inner tube, means for

closing the open ends of said compartments whereby the inner tube will be completely inclosed within the container, and means for connecting the respective ends of the container when the same is folded in half to form a compact package.

5. A container for inner tubes for pneumatic tires formed from a flexible material and provided with spaced compartments aligned to permit of the insertion of one half

of a folded tube in each compartment, means for protecting the portion of the inner tube located within the space between said compartments, said means being formed to permit of the passage of the valve stem of the inner tube therethrough, and means for securing the respective ends of said container together when folded in half. 15

WILLIAM J. ROSTERN.
